CLAIM

The ornamental design for a hand held bar code reader for inventory control, as shown and described.

DESCRIPTION

FIG. 1 is a front, top and side perspective view of the hand held bar code reader for inventory control showing my new design;

FIG. 2 is a front elevational view thereof;

FIG. 3 is a rear elevational view thereof;

FIG. 4 is a side elevational view thereof;

FIG. 5 is an opposite side elevational view thereof;

FIG. 6 is a top plan view thereof; and,

FIG. 7 is a bottom plan view thereof.

The slip of paper is shown in broken lines in FIG. 1 for illustrative purposes only and forms no part of the claimed design.
